COMBINED ASH TRAY AND COASTER OR SIMILAR ARTICLE

Jack Lane, Los Angeles County, Calif.

Application February 24, 1955, Serial No. 34,678

Term of patent 3½ years

(Cl. D85—2)

Fig. 1.

Fig. 2.

Fig. 3.

Fig. 4.

Fig. 5.

Fig. 1 is a top perspective view of a combined ash tray and coaster or similar article, showing my new design;

Fig. 2 is a cross-sectional view thereof, taken along the longitudinal axis thereof;

Fig. 3 is a front elevational view thereof;

Fig. 4 is an end elevational view thereof; and

Fig. 5 is an opposite end elevational view thereof.

The broken line showing of articles contained therein in Fig. 2 are for illustrative purposes only. The surfaces thereof are diagonally lined to indicate transparency.

I claim:

The ornamental design for a combined ash tray and coaster or similar article, as shown and described.
